UNITED STATES PATENT OFFICE.

JOSEPH J. GRAMMES, OF LAKEWOOD, OHIO.

AUTOMOBILE TURN-TABLE.

1,083,609.

Specification of Letters Patent.

Patented Jan. 6, 1914.

Application filed August 4, 1913. Serial No. 782,866.

To all whom it may concern:

Be it known that I, JOSEPH J. GRAMMES, a citizen of the United States, resident of Lakewood, county of Cuyahoga, and State 5 of Ohio, have invented a new and useful Improvement in Automobile Turn-Tables, of which the following is a specification, the principle of the invention being herein explained and the best mode in which I have 10 contemplated applying that principle, so as to distinguish it from other inventions.

My invention relates to turn-tables, and particularly to turn-tables adapted for use in connection with the housing of automo- 15 biles.

The object of the invention is to provide a turn-table which will be transferable and which will eliminate the necessity of providing a permanently located track upon 20 which the table proper is supported.

My said invention consists of means hereinafter fully described and particularly set forth in the claims.

The annexed drawing and the following 25 description set forth in detail certain means embodying my invention, the disclosed means, however, constituting but one of various mechanical forms in which the principle of the invention may be applied.

30 In said annexed drawing: Figure 1 is a plan of an automobile turn-table embodying my invention. Fig. 2 is a side elevation of same. Fig. 3 is a bottom plan of same. Fig. 4 is a detail section, upon an enlarged scale, 35 taken upon the plane indicated by line IV—IV in Fig. 1. Fig. 5 is a detail section on a similar scale taken upon the plane indicated by line V—V in Fig. 1. Fig. 6 is a side elevation of a fragmentary portion of the de- 40 vice showing a braking device applied to one of the supporting rollers. Fig. 7 is a side elevation of one of the extension-members.

The illustrated embodiment of my invention 45 comprises two main members, the base-frame 1 and the table proper 2. The base-frame includes two angle-members 3 3 each bent to form a continuous ring and having similar legs placed vertically and opposing 50 each other to form an annular space 4, as illustrated in Fig. 4, the other legs being

horizontal and in the same plane. These two members are fixed relatively to each other by means of suitable tie-plates 5 preferably riveted to the bottom of the horizontal legs of the angle-members 3 3, as shown in Fig. 3. To the bottom of the latter are also secured the radial tie-members 6 6 whose inner ends are secured to a suitable gusset-plate 7, these members being 60 provided for stiffening the ring-portion of the frame, as will be readily understood. Also secured to the bottom of this ring-portion are a plurality of castings 8 8 which support a plurality of parallel rods 9 9. 65 Upon each rod is mounted a pair of supporting rollers 10 10, by means of which it will be seen that, when these rollers are resting upon the ground or other support, the base-frame is rendered mobile and is 70 capable of being transferred from place to place. Secured to the vertical legs of the angle-members 3 3 and extending across the annular space, are a plurality of bearing-bolts 11 11, upon each of which is mounted 75 an anti-friction roller 12, Fig. 4.

The table proper comprises in its structure a bottom-portion which consists of a T-member 13 bent to form a ring of a diameter such that the web-portion may rest centrally upon the anti-friction rollers 12, as shown in Fig. 4, which position is that which said member occupies when the parts are assembled. Also comprising a part of the table proper, resting upon the top of the T- 80 member 13 and suitably secured thereto, are two main track or guide-members 14 14 whose corresponding ends are connected by means of transverse connecting bars 15, which bars are connected by a longitudinal 85 channel-bar 16, Fig. 1. This last bar is also preferably secured by a riveting or bolting to the upper surface of the member 13. A centering-pin or king-bolt 17, Fig. 5, passes through the channel-bar 16 and the gusset- 90 plate 7 and maintains the concentricity of the member 13 with the annular space 4, that is the concentricity of the table with the supporting-base, as will be readily understood. 95

Forming a part of and the end of each track or guide-member 14 is an auxiliary

track or guide-member 18, Fig. 1. Each of these latter members is hinged to the end of a member 14 and is normally held in a raised position by means of a suitable spring 5 19, Figs. 2 and 3, while at the same time it also occupies a downwardly extending position. The extreme outer end of each of these members is curved downwardly and outwardly flared. It will therefore be seen 10 that when the entire structure rests upon a support engaged by the supporting-rollers 10, the track-members 18 would be out of contact with such support and its rotation upon the rollers 12 will be unhindered. 15 In using the above described device for turning an automobile, the latter is run up to the turn-table until its front wheels come in contact with the two end members 18 18 at one end of the device. A further movement 20 of the automobile forward will cause the front wheels to depress said members 18 until their extremities come in contact with the ground or support upon which the rollers rest, and these end-members will therefore 25 form an incline by means of which the automobile may be run up upon the main track or guide-members 14. Upon being so placed, the automobile may be turned by swinging same and hence turning the table 2 upon the 30 base-frame, the end-members 18 18 having assumed their normal or raised position after the automobile has been placed upon the members 14 14. When the required position of the automobile has been imparted, it 35 may then be run off the table proper, the end-members 18 18 being depressed and acting as an incline for such movement. When the direction of movement of the automobile is at right angles to the axes of the rollers 10, 40 the tendency of the entire structure would be to move, rolling upon the supporting-rollers 10. To prevent such movement I provide a braking device, preferably applied to each of two rollers mounted upon the 45 same rod 9 and as shown in Fig. 6. This brake consists of oscillatory member 20 hinged in the vicinity of one of said rollers and formed with a concave surface 21 having a curvature substantially similar to that 50 of the exterior surface of said roller. The axis of this member 20 is so located that the member may be swung down into a position in which the said roller enters the concavity formed and engages the concave surface 21, 55 the extremity of the said member 20 passing beneath the roller and interposing itself between same and the ground or other support upon which the structure rests, as shown in dotted lines in Fig. 6. In order to 60 hold the brake-member in a normal or elevated and inoperative position, a resilient detent 22 is provided which may engage the projection 23 on the brake-member 20, as shown in Fig. 6. Pressure upon the outer

end of the said brake-member will release 65 the projection 23 from the detent and permit the operative position to be assumed.

In order to make the table proper adjustable so as to accommodate automobiles of increased length, each track or guide-member 70 14 may be provided with an extension 24, Figs. 1 and 7. Each such extension, as illustrated, consists of a flat plate provided with a downwardly projecting pin 75 25 formed with a hinged head 26. This pin is caused to engage a keyhole-slot 27 formed in each of two corresponding ends of the said track-member, as shown in Fig. 1. By these means it will be seen that the length of each of the said track or guide-members may 80 be extended when desired. The keyhole-slot and pin arrangement makes the extension readily applicable or removable.

In order to readily transfer the turn-table from place to place, a suitable handle 28, 85 Fig. 1, may be provided and is preferably made detachable. When it is desired to transfer the device, the table is swung so that the direction of the detachable handle will be at right angles with respect to the 90 axes of the rollers 10, as will be readily understood.

By means of the above described structure it will therefore be seen that a turn-table is provided which may be transferred from 95 place to place with ease and which in any position and upon any character of support for the rollers 10, will always permit the table proper to be rotated without interference. In this manner an efficient turning 100 device is provided without the necessity of installing a permanently located track, as is usually necessary, whereby the space in front of an automobile garage may be always unobstructed. Furthermore the expense of installation of such a permanent track is eliminated.

Having fully described my invention, what I claim and desire to secure by Letters Patent is:—

1. In a turn-table, the combination of a base-frame consisting of two concentric angle members forming an annular space, anti-friction rollers mounted in said space, and supporting rollers for rendering said 115 base-frame mobile; of a table comprising a circular member of T-section having its web resting upon said anti-friction rollers, and parallel track or guide-members secured to the flange of said T-member.

2. In a turn-table, the combination of a base-frame consisting of two concentric angle members forming an annular space, anti-friction rollers mounted in said space, and supporting rollers for rendering said 125 base-frame mobile; of a table comprising a circular member of T-section having its web resting upon said anti-friction rollers, par-

allel track or guide-members mounted upon the said T-member and secured to the flange thereof; and a centering pin connecting said base-frame and table adapted to maintain the concentricity of said T and angle-members.

5. In a turn-table, the combination of a base-frame provided with supporting rollers adapted to render said frame transferable;

a table rotatably mounted upon said base-frame; and braking-means for engaging one or more of said supporting rollers.

Signed by me, this 18th day of July, 1913.

JOSEPH J. GRAMMES.
